LEAF HOLDING DEVICE

Berkeley S. Vaughan, Geneva, Ill., assignor to
Leon Wheeler, Geneva, Ill.

Application April 10, 1937, Serial No. 136,032

2 Claims. (Cl. 129—8)

My invention relates to an improvement in leaf holding devices which is particularly applicable to the visible holding of multiple sheet systems. It may be employed for example to hold ledger sheets or to hold overlapping filing cards or sheets, the particular sheets with which my device is employed forming no part, of themselves, of the present invention.

One purpose is the provision of ready means for holding a plurality of sheets in such fashion that they may be visibly inspected and, while firmly held in position during inspection and storage, may very readily be released for the removal or insertion of one or more or all of the sheets involved.

Another purpose is the provision of improved means for holding such sheets, as a group, in a file, ledger case, backing, or the like.

Another purpose is the provision of means for readily removing the sheets as a group or unit from the support in which they are normally positioned.

Another purpose is the provision of improved means for holding them firmly in position while ready for practically instantaneous removal.

Another purpose is the provision of filing means, employing straight posts, which will effect a maximum economy of space and as contrasted, for example, to filing systems in which books with rings or curved posts are employed.

Other purposes will appear from time to time in the course of the specification and claims.

I illustrate my invention more or less diagrammatically in the accompanying drawings wherein:

Figure 1 is a plan view, with parts in section;

Figure 2 is a section of the line 2—2 of Figure 1;

Figure 3 is a section on the line 3—3 of Figure 1;

Figure 4 is a plan view of the structure of Figure 1 with the parts in a different position;

Figure 5 is a detail;

Figure 6 is a side elevation;

Figure 7 is a section on the line 7—7 of Figure 5.

Figure 8 is a plan view of a form of my device;

Figure 9 is a side elevation of the structure of Figure 8; and

Figure 10 is an enlarged section on the line 10—10 of Figure 8.

Like parts are indicated by like symbols throughout the specification and drawings.

Referring to Figures 8, 9 and 10, I illustrate a form of unit which may be employed with any

suitable base or securing structure. I show it as including a side or binder bar 27 with headed pins 28 secured thereto. The opposite bar 29 is shown as having keyhole apertures 30 to receive these heads and a spring 31 with an aperture 32 adapted to engage one of the heads and to hold the bar 29 in locked position. The bar 29 may also be provided with sliding pins 33, each said pin being provided with an enveloping member 34 partially surrounding and sliding upon the side bar 29.

34a indicates abutments or upset portions in the strip or bar 29 adapted to limit the endwise movement of the enveloping members 34, whereby an unintended escape of the movable pins 33 is prevented.

Referring to Figures 1 to 7, I illustrate a unit which may include a side bar 90 having a bottom 91 formed integrally therewith and an opposite flange 92. The bottom 91 is provided with an aperture 93 having a tongue 94 at one end thereof. A base portion 95 is provided which has an upwardly extending block shaped member 96 having an aperture 97 at one end thereof adapted to receive the tongue 94. The unit may be locked in position by dropping it with the aperture 93 receiving the member 96 as shown in Figure 4. The unit is then slid downwardly into the position in which it is shown in Figure 2 with the tongue 94 penetrating the aperture 97. A spring latch 98 then urges the locking member 99 down into the aperture 100 in the base and locks the unit against unintended movement. An opposite side bar 101 may be employed having keyhole apertures 102 receiving the heads 104 of pins 103 on the binder bar flange 90. It may also carry slidably mounted leaf penetrating pins or fingers 105 and the locking spring latch 106.

It will be realized that whereas I have described and illustrated practical and operative devices, nevertheless many changes may be made in the size, shape, number and disposition of parts without departing from the spirit of my invention. I therefore wish my description and drawings to be taken as in a broad sense illustrative or diagrammatic rather than as limiting me to the precise showing.

The use and operation of my invention are as follows:

95 indicates any suitable base upon which my device may be mounted. It will be understood that the base may be of wood or metal or any other suitable material, but I illustrate it as formed of or including a metal plate 95. It will be understood also that a plurality of the above

described units may be arranged on the base side by side, the units as such being adaptable for such fixed mounting, or, if desired, to be inserted in any suitable book or binder not herein shown.

5 The leaf engaging or clamping unit shown in Figures 1 to 7 includes one side bar 90, which includes a bottom portion 91, which serves as the means of attachment to the base 95. It will be understood that I may employ also the structure shown in Figures 8, 9 and 10, in which the side bars 27 and 29 are both flat and parallel, and any suitable means may be employed for securing the ends as a whole to any suitable base, binder or the like, which does not of itself form 10 part of the present invention. In either form, however, a group of leaves is confined between side bars 90 and 101, or 27 and 29. In each case binding pins 28 or 103 are fixed to one of the side bars, and movable or slideable posts 105 or 33 15 are slideably mounted upon the opposite side bar. Slideable pins are provided with the enveloping members 34, which slideably support them on the side bars 29 or 101, respectively.

This structure is advantageous in adding leaves or withdrawing leaves from the group of leaves between the two side bars. In prior art practise it is normal to employ a supplemental bar of some kind, or a temporary securing means, in order to prevent disassociation or misalignment of the leaves, if leaves are being inserted or removed in 20 a body of leaves, when part of the body is laid in one direction and part in another. A supplemental bar with binder posts on it has in the past been customarily employed in order to prevent 25 displacement or misalignment of the leaves. This is particularly the case where a binder is employed to secure groups of overlapping or staggered record pages where the individual pages are considerably shorter than the strips and are overlaid one upon the other so that the bottom or lower portion of each page is unmasked by the 30 page above. The present structure provides a ready solution of this problem by the employment of slideable pins. The employment of these 35 sliding pins permits a ready relative endwise movement of the two strips in order to release the locking means, without the necessity of drawing the strips out so far as to free the two sets 40

of binder posts. Since the binder posts on one strip slide, the two strips can readily have imparted to them a relative endwise movement without separating them by any substantial movement and without unintentionally releasing 5 any of the leaves.

I claim:

1. In a securing unit for leaves and the like, two strips of sheet metal, a plurality of binding posts fixed upon one of said strips perpendicular 10 to a face thereof, each said binding post having a head portion, the opposite strip having keyhole shaped apertures, the large portions of which are of sufficient size to admit said heads, the smaller portions of which are of a size insufficient to 15 permit the escape of said heads therethrough, whereby, when said strips are given a relative endwise movement in generally parallel planes, said binding posts are gripped by the small portions of said keyhole apertures, means for preventing unintended relative endwise movement 20 of said strips, including a spring secured to the exterior of the apertured strip, said spring having an aperture overlying the smaller portion of one of said keyhole apertures and being biased 25 to close approach to the opposed face of said strip, whereby the aperture in said spring is adapted to receive the head of one of said binding posts, and additional binding posts mounted on said opposite strip, the ends of said additional binding posts terminating adjacent the 30 opposed face of the first named strip when the strips are assembled, means for mounting the binding posts of said opposite strip for longitudinal sliding movement with respect thereto. 35

2. In a securing device for leaves and the like, a unit including a pair of binder bars, each of said bars being provided with leaf engaging posts, one of said bars being apertured to receive the free ends of the posts of the other bar, means 40 carried by the apertured bar for releasably locking the same to the free ends of the posts of the other bar, when said post ends are entered in said apertures and said bars are relatively shifted longitudinally, and means providing for relative 45 sliding movement between one of said binder bars and the posts thereof.

BERKELEY S. VAUGHAN.
